ELECTRIC LIGHTING DEVICE AND MANUFACTURE THEREOF

Harry A. Douglas, Bronson, Mich., assignor to
Kingston Products Corporation, a corporation
of Indiana

Application January 21, 1935, Serial No. 2,723

16 Claims. (Cl. 176—7)

My invention relates to electric lighting devices and the making of such devices. More particularly, my invention relates to electric lighting devices such as are mounted in reflectors, as in automobile head-lamps, and the making of such devices. The principal object of my invention is to provide a new and improved device of these types, including a new and improved method and apparatus for making the same. In the drawings accompanying this specification, and forming part of this application, I have shown, for purposes of illustration, certain forms which my invention may assume; in these drawings:

Figure 1 is a side elevational view, partly in section, of one embodiment of my invention,

Figure 2 is a fragmentary view of one face of a mounting,

Figure 3 is a perspective view of a detail of Figure 1,

Figure 4 is a front view of a mounting, with the detail of Figure 3 not completely assembled therewith,

Figure 5 is a front view, of the parts shown in Figure 4, completely assembled,

Figure 6 is a section taken along the line 6—6 of Figure 1,

Figure 7 is a fragmentary sectional view, enlarged, taken on the line 7—7 of Figure 6,

Figure 8 is a view similar to Figure 7 with the parts in a different position,

Figure 9 is a side elevational view, partly in section, of another embodiment of my invention,

Figure 10 is a front view, partly in section, of parts of the embodiment of Figure 9, partly assembled,

Figure 11 is a sectional view of the same parts as in Figure 10, with the parts completely assembled, the section being taken along the line 11—11 of Figure 9,

Figure 12 is a detail view of a part illustrated in Figures 9 through 11,

Figure 13 is a view of a detail similar to Figure 12 but with the parts in a different position, and

Figure 14 is a side elevation, partly diagrammatic, of apparatus for carrying out the method of making one of the parts of the embodiments hereinbefore referred to, said figure including also another embodiment of said part.

Referring to Figure 1, there is here shown an incandescent electric lamp 20 connected to a mounting 21. The mounting 21 may be a reflector of parabolic form. The lamp 20 comprises a bulb 22 containing a pair of filaments 23, 24. The filament 23 is here shown as disposed on the axis of the lamp, whereas the filament 24 is dis-

placed from that axis. The lamp 20 includes means providing a base 25 for the lamp. The base means here shown includes a generally cylindrical shell member 26 in which the bulb 22 is secured in a well known manner. The base means includes a lateral extension, which in this instance is shown as including a cylindrical portion 27 surrounding the shell 26, the cylindrical portion 27 being integrally joined to another cylindrical portion or skirt 28 by a curved annular portion 29. The skirt 28 is spaced from the shell 26, and may have its edge 30 rounded if desired. The cylindrical portion 27 may be fastened to the shell 26 in any suitable manner. The skirt portion 28 is provided with a plurality of laterally extending portions 31, 32, 33. The portions 31, 32, 33 are shown as struck out from the skirt 28, and each struck out portion is shown as comprising a pair of radially outwardly extending portions 34, 35 and a circumferential portion 36, joining the ends of the radially extending portions 34, 35, the portions 34, 35, 36 forming an aperture extending in an axial direction.

The mounting 21 is provided with a circular aperture 37, the diameter of which is enough larger than the diameter of the skirt 28 so that the skirt 28 may be readily slipped through the aperture 37.

The base 25 is adapted to cooperate with a socket means or connecting means 38. For convenience the connecting or socket means will be referred to as socket means. The socket means comprises a generally cylindrical shell 39 provided with a radially extending flange 40 from which extend in an axial direction a plurality of circumferentially spaced portions or bars 41, 42, 43, shaped in this instance to form hooks. All of these hooks, in the illustrated embodiment, are of the same form so that in the following description reference may be had to the hook 43 which may be most clearly seen in Figure 3.

The hook 43 comprises a throat 44 and a mouth 45 which is partly closed by a lip 46. The lip 46 is of triangular form providing a pair of cam surfaces 47, 48. If desired the end of the hook may have its corners 49, 50 beveled off. The cam surface 47 extends to the bottom 51 of the mouth of the hook.

The width of the hook between the outer edge 52 of the lip 46 and the edge 53 of the back of the throat 44 of the hook is such as to pass freely through apertures 54, 55, 56 respectively, in the mounting 21. The apertures 54, 55, 56 are here shown as constituting radial extensions of 55

the aperture 37. The throat 44 of each hook is of a width to fit the circumferential width of a set of apertures 57, 58, 59 respectively, which apertures also are here shown as constituting radial extensions of the aperture 57. The apertures 54, 57 and 55, 58 and 56, 59 are separated respectively by radially inwardly extending projections 60, 61, 62, the sides of these projections defining edges of the apertures 57, 58, 59 being 10 substantially radial, whereas the other sides are in the form of cam surfaces 63, 64, 65.

The radially outer margins of the apertures 54, 55, 56 and 57, 58, 59 lie on a circle having a diameter substantially the same as the diameter of the 15 cylindrical surface defined by the outer peripheries of the hooks 41, 42, 43, the radial extent of these apertures being substantially the same as the radial thickness of the hooks.

In connection with one use to which the 20 embodiment of Figures 1 through 8 may be put, the hooks 41, 42, 43 are desirably unequally spaced about the axis of the socket means 38, the sets of apertures 57, 58, 59 and 54, 55, 56, and the extensions 31, 32, 33, being correspondingly 25 unequally spaced about the center of the aperture 37 and the axis of the base of the lamp respectively, as illustrated in Figures 1 through 6.

The socket means 38 is provided with an insulating member 66, adjacent one side of which 30 are radially inwardly extending diametrically opposite segmental flanges 67, 68 provided on the shell portion 39. The insulating member 66 may be fastened to the shell portion 39 by means of tongues, two of which 69, 70 are visible in Figure 35 1. These tongues may be clinched over the outside of the insulating member 66. A composite leaf spring 71 may be interposed between the insulating member 66 and the segmental flanges 67, 68, so that the spring is also held between 40 the flanges and the clinched-over tongues 69, 70. The spring 71 may include an annular part 72, having an aperture large enough to pass the shell 39, the part 72 being provided with a desired number of radially inwardly extending projections 45 73 against which the insulating member 66 is adapted to be pressed. The spring 71 is here shown as provided with three legs, two of which 74, 75 are visible in Figure 3. The legs 74, 75 of the spring are bowed radially outwardly intermediate their ends and their point of connection 50 to the annular portion 72.

The insulating member 66 is here shown as carrying a pair of contacts 76, 77, each of these contacts being connected to a conductor, only one 55 of which, 78, is visible. The conductor passes through a sleeve 79 provided with a flange 80 adapted to be engaged by the head of the contact 76. The sleeve 79 is slidable in a bushing 81, the bushing passing through the insulating 60 member 66 and being fixed thereto in any suitable manner as by providing beads 82 on the bushing. A spring 83 is provided for urging the contact 76 away from the insulating member 66, the spring 83 at one end abutting the flange 80 and at the other end the bushing 81. The contact 65 77 is similarly resiliently mounted.

The contacts 76, 77 are adapted to engage a pair of contacts 84 provided on the base of the lamp 20, only one of the contacts 84 being visible 70 in Figure 1. The filament 23 of the lamp may have one of its terminals connected to one of the contacts 84 and its other terminal to the shell 26. The filament 24 may likewise have one of its terminals connected to the shell 26 and 75 its other terminal connected to a different one

of the contacts 84, as will be obvious to those skilled in the art.

The assembly and operation of the embodiment of the invention illustrated in Figures 1 through 8 is as follows. When it is desired to assemble the socket means 38 with the mounting 21, the hooks 41, 42, 43 are inserted through the apertures 54, 55, 56 respectively, against the bias of the composite spring 71, the ends of which abut the rear face of the mounting, until the lip portions 46 of the hooks extend beyond the front face of the mounting 21. The parts are then in the position shown in Figure 4. The socket means is then rotated in a counter clockwise direction, as viewed in Figure 4. Such rotation causes the throat portions 44 of the hooks to engage the cam surfaces 63, 64, 65, thereby forcing the throat portions radially inwardly. Counter clockwise rotation of the socket means is continued until the trailing edges 53 of the throat portions 44 snap off of the projections 60, 61, 62, the throat portions moving radially outwardly and becoming seated in the apertures 57, 58, 59. The parts are then in the position shown in Figure 5. When axial pressure on the socket means is removed, the composite spring 71 acts to move the socket means axially toward the right as viewed in Figure 1, thereby pulling the apexes of the triangular lips 46 against the front face of the mounting 21.

The socket means and mounting are now ready to have an incandescent lamp connected thereto. The lamp, such as 20, may have its base 25 brought into register with the inner periphery of the hook portions 41, 42, 43, and with the lateral extensions 31, 32, 33 so positioned that by moving the lamp 20 axially toward the mounting 21 the extensions 31, 32, 33 will come into abutment with the front face of the mounting 21. The lamp 20 is then rotated toward the mouth portions 45 of the hooks to thereby bring the leading portions 35 of the lateral extensions 31, 32, 33 against the respective cam surfaces 48 of the lips of the hooks, as shown in Figure 8. Further rotation of the lamp 20 in the same direction causes the portions 35, by cam action on the surfaces 48, to pull the hooks 41, 42, 43 further through the mounting 21, against the bias of the composite spring 71. When the trailing edge of the portion 35 passes the apex of the lip portions 46, the parts are brought to the position shown in Figure 7 in which the ends of the lip portions 46 of the hooks are disposed in the axially extending apertures formed between the radial portions 34, 35 of the extensions 31, 32, 33. The parts are so proportioned that the apex of the lip portions 46 is then out of contact with the front face of the mounting 21, so that surfaces of the lateral extensions 31, 32, 33, opposed to the face of the mounting, are maintained in firm engagement and registry with the front face of the mounting 21.

The hereinbefore described embodiment of my invention is well adapted for use where the aperture 37 is an aperture located in the crown of a parabolic reflector, concentric with the axis of the reflector. For such use the lamp is pre-focused, that is, the position of the lateral extensions 31, 32, 33 is so chosen that the general plane of these extensions is so positioned that the lighting center of the filament 23 is not only on the axis of the reflector but is at the focal point of the reflector. The filament 24, which may be used either alone or in combination with the filament 23, therefore is also disposed at a

predetermined position with respect to the reflector, for the reason that the lamp 20 may be connected to the reflector at but one predetermined position about its axis because of the unequal spacing of the apertures 57, 58, 59 and the correspondingly unequal spacing of the hook portions 41, 42, 43 and the lateral extensions 31, 32, 33. Furthermore, the contacts 84 in the base are caused to properly engage the desired respective contacts 76, 77 so that the switching device (not shown) connected to the contacts 76, 77 will be able to cause current flow in the filaments 23, 24 in the desired relations.

Figures 9 through 13 illustrate another embodiment of my invention, in which the lamp 20, here shown as identical with the lamp 20 of Figure 1, is assembled with a mounting 85 having a circular aperture 86 which is of such diameter as to freely pass the skirt 28 of the base 20 of the lamp 20.

A connecting means or socket means 87 is provided, having a shell portion 88. The shell portion 88 has a radial flange 89 provided with axially circumferentially spaced portions 90, 91, 92 made in the form of hooks. The outer peripheries of the portions 90, 91, 92 define a cylindrical surface, with exceptions to be noted hereinafter.

Each hook has a throat portion 93 and a mouth 94, along with a lip portion 95 partially closing the mouth of the hook. The lip 95 may have a beveled outer corner to act as a cam surface, if desired. The bottom 96 of the mouth of each hook is adapted to overlie portions 97, 98, 99 of the mounting 85. The radially inner edges of the portions 97, 98, 99 are defined by the aperture 86.

The edges of each of the hooks 90, 91, 92 opposite the lips 95, are undercut from the ends 40 of the hooks, the undercut extending axially along a line 100, partially into the throat portion 93, to a shoulder 101. The shoulder 101 is axially spaced from the bottom 96 of the mouth of the hook by an amount substantially the same as the thickness of the mounting 85.

The throat portions 93 of the hooks to and including the edges 100 of the hooks are bent radially outwardly, so that, as can be seen in Figures 10 and 11, the bent throat portions 50 have radially outer surfaces tangent to the cylindrical surface defined by the hooks 90, 91, 92. Those portions of the throat portions 93 which terminate in the shoulders 101 are also bent radially outwardly, in this instance slightly more than the edges 100.

The reduced parts of the throat portions 93 of the hooks are adapted to be seated in apertures 102, 103, 104 in the mounting 85. The lips 95 of the hooks are adapted to be seated in apertures 105, 106, 107 respectively. The apertures 102, 103, 104 and 105, 106, 107 are here shown as constituting radially outwardly extending portions of the aperture 86 to thereby form the portions 97, 98, 99 of the mounting, of a radial extent substantially the same as the thickness of the hooks.

The mounting 85 is provided with another set of apertures 108, 109, 110, which, when the hooks 90, 91, 92 are assembled with the mounting, are adjacent the circumferentially outer edges of the lips 95, and extend radially beyond the radially outer margins of the apertures 105, 106, 107.

The mounting 85 is provided with another set of apertures 111, 112, 113 adjacent the set of apertures 102, 103, 104, and both of these sets

of apertures have radially outer margins which are at an angle to a radius of the aperture 86, substantially the same as the angle of the tangent bent portion of the throats 93. These sets of apertures consequently form triangular projections 114, 115, 116, the apexes of which lie on a circle larger than the aperture 86 by an amount substantially equal to the radial thickness of the hook portions 90, 91, 92. The circumferential width of each of the pairs of apertures 102, 103 and 103, 102 and 104, 103 is sufficient respectively to pass the circumferential width of the reduced ends of the hooks respectively. Due to the unequal circumferential spacing of the apertures 102, 103, 104, the aperture 102 merges with the aperture 110.

The socket means may be provided with an insulating contact carrier 117 similar to the contact carrier 66 of Figure 1, but in this instance no spring 71 is provided, so that the contact carrier 117 directly abuts radially inwardly extending segmental flanges 118, 119 on the shell portion 88. The contact carrier 117 may be fastened to the shell member 88 by means of clinched tongues 120.

The contact carrier 117 is here shown as carrying a pair of contacts 121, 122 which are connected to conductors and resiliently biased toward the contacts 84 on the lamp base in a manner the same as already described in connection with Figure 1.

The embodiment of the invention illustrated in Figures 9 through 13 is assembled and operated in the following manner. The hook portions 90, 91, 92 are brought into registry with the pairs 35 of apertures 102, 103 and 103, 102 and 104, 103 respectively and thrust through these composite apertures until the shoulders 101 abut the rear face of the mounting 85. The socket means is then rotated in a counter clockwise direction, 40 as viewed in Figure 10, whereby the triangular portions 114, 115, 116 force the hooks radially inwardly. As the counter clockwise rotation continues the leading edges of the lips 95 ride radially inwardly up onto the inner peripheries 45 of the mounting portions 97, 98, 99, which action may be assisted by the beveled edges of the portions 97, 98, 99. Further counter clockwise rotation causes the trailing edges of the lips 95 to snap into the apertures 105, 106, 107. At the same time the trailing edges 100 of the hooks snap off of the triangular projections 114, 115, 116, thereby seating the reduced portions of the necks 93 in the apertures 102, 103, 104 respectively. The parts are then in the position shown 55 in Figure 11, in which the socket means is latched both against rotational movement in either direction, and against any substantial axial movement in either direction.

In the assembled position of the socket means 60 in the mounting 85, the lips 95 of the hooks extend in an axial direction toward the right, as viewed in Figures 9, 12, and 13, beyond the rear face of the mounting 85, a predetermined desired amount.

The parts as shown in the position in Figure 11 are ready to receive and have connected thereto a lamp 20. The lamp is first brought into registry with the skirt 28 of the base in registry with the aperture 86, and with the lateral extensions 31, 32, 33 in registry with the apertures 108, 109, 110. The lamp is then moved axially, against the bias of the contacts 121, 122, thereby causing the lateral extensions 31, 32, 33 to pass through the apertures 108, 109, 110 to a position 75

- axially beyond the rear face of the mounting 85. The lamp 20 may then be rotated in such direction that the lateral extensions 31, 32, 33 enter the mouth portions 94 of the hooks, whereupon the lamp may be released, the resiliently biased contacts 121, 122 moving the projections 31, 32, 33 towards the bottoms 96 of the mouth portions 94, and seating those projections directly against the rear face of the mounting 85, as can be seen from Figures 9 and 13. The resiliently biased contacts 121, 122 not only force the projections 31, 32, 33 against the rear face of the mounting 85 but force the bottoms 96 of the hooks against the front face of the mounting.
15. As in the embodiment of Figures 1 through 8, the embodiment of Figures 9 through 13 is adapted to be used in instances where the aperture 86 is located on the axis of a parabolic reflector. For reasons already pointed out in connection with Figures 1 through 8, the lamp 20 may be of the pre-focused type, which is accomplished by properly locating the lateral extensions 31, 32, 33 on the base with respect to the filament 23 and with respect to the focal point of the reflector.
20. The lateral extensions 31, 32, 33 may be properly located on the base by making a lamp, complete except for the lateral extensions or positioning means 31, 32, 33, then adjusting such a lamp to a predetermined position and then while the lamp is in that predetermined position forming the positioning means on the base.
25. This method may be carried out by apparatus, one embodiment of which is illustrated in Figure 14.
30. The apparatus shown in Figure 14 includes a support 123 desirably of insulating material, carrying a pair of contacts 124, 125 connected to conductors 126, 127 respectively. The contacts 124, 125 may, if desired, have slightly dished contact surfaces. The conductors 126, 127 are disposed through sleeves 128, 129 which are in turn slidable in bushings 130, 131 suitably fixed to the support 123. The contacts 124, 125 are biased upwardly by springs 132, 133, and in general, the contacts 124, 125 may be supported and biased in a manner similar to that already described in connection with the contacts 76, 77, of Figure 1.
35. The contacts 124, 125 are adapted to be engaged by contacts 134, 135 carried by the lamp 136. The lamp 136 is similar to the lamp 20 hereinbefore described, but in this instance the lamp may have a bulb 137 which is mounted in a base 138 having a shell portion 139 and a skirt portion 140 which is an integral part of the shell 139, spaced therefrom and connected thereto by the curved annular portion 141. The principal difference between the lamp 136 and the lamp 20 is that the skirt portion 140 forms an integral part of the shell 139, whereas in the lamp 20 the base means is made in two parts comprising generally a shell portion 26 and the skirt portion 28 suitably fastened thereto. The lamp 136, as in the case of the lamp 20, may be provided with a pair of filaments 142, 143.
40. The lamp 136 may be held with its contacts 134, 135 in engagement with the contacts 124, 125, and adjusted with respect to these contacts and the support 123, by means which includes a dished member 144 adapted to engage the top of the bulb 137. The member 144 may be provided with a stem 145 slideable through an aperture 146 in a lever 147. The movement of the stem 145 may be limited by a collar 148 on the stem. Where the stem 145 is movable with respect to the lever 147, a spring 149 may be interposed

between the dished member 144 and the lever, biasing the member 144 away from the lever.

The lever 147 is here shown as connected by means of a ball and socket joint 150 to a lever 151. The lever 151 may be provided with a 5 socket 152 adapted to receive a ball 153 on the end of the lever 147. The opening 154 may be limited so as to limit the range of movement of the lever 147 with respect to the lever 151.

The lever 151 may be mounted to swing in one 10 plane about the pivot 156 carried by a bracket 155. The bracket may be provided with stops 157, 158 to limit the range of movement of the lever 151. The lever 147 is desirably provided with a handle 159.

15. Die means 160 are provided for forming the positioning means on the lamp base. For the sake of clearance only one die means has been shown, but it is to be understood that at least one other die means is preferably utilized, and in 20 the case of making pre-focused lamps preferably three die means are used. The three die means are then disposed at equal radial distances from a line, midway between the axes of the contacts 124, 125, parallel to said axes. Furthermore, the 25 three die means are desirably spaced circumferentially at predetermined points with reference to the general plane of the contacts 124, 125.

The die means 160 is here shown as including a pair of dies 161, 162, the die element 161 being of 30 the matrice type and the die element 162 of the punch type. The matrice die element has a recess 163, which is of the same axial length as that of a punch projection 164 on the die element 162. The circumferential width of the recess 163 is the 35 same as the desired circumferential distance between the outer faces of the radially extending portions 34, 35 of the lateral extensions 31, 32, 33. On the other hand, the circumferential width of the punch portion 164 is the same as that between the inner faces of the portions 34, 35. It of course will be understood that the shape and dimensions of the matrice and punch portions of the die means 160 will depend upon the form of lateral extensions it is desired to make.

45. The die elements 161 and 162 may have their opposing faces provided with recesses 165, 166, to enable a skirt portion such as 28, having a rounded edge 30, to be properly worked upon.

The die elements 161, 162 are shown as mounted 50 on a pivot 167 carried by a lever 168. The die elements 161, 162 are provided respectively with cam surfaces 169, 170 together forming a V-shaped recess. The die elements 161, 162 may be biased away from each other by a spring 173 55 having its ends engaging pins 171, 172 mounted on the elements 161, 162 respectively. Separation of the upper ends of the die elements 161, 162 is limited to a predetermined extent by engagement of the pin 171 with the cam surface 170.

60. The lever 168 may be mounted on a pivot 174 on a stationary bracket, and may be biased to a predetermined position by means of springs 177, 178 respectively. The spring 177 may have one end attached to a stationary bracket 175 and the other end to a pin 179 on the lever 168, and the spring 178 may have one end attached to the pin 179 and the other end to a stationary bracket 176.

65. The die elements 161, 162 may be moved toward each other by means of an operating member 180 having at the upper end thereof two cam surfaces 181, 182 forming a V-shaped cam cooperable with the cam surfaces 169, 170. It is to be understood that there will be as many operating mem- 70 75

bers 180 or equivalent elements as there are die means 160.

The operating member 180 is carried by a member 183 extending at right angles thereto and adapted to be reciprocated in any suitable manner. In the form of the apparatus shown the member 183 is reciprocable by means of a non-magnetic member 184 to which is attached a magnetic core 185 cooperable with a solenoid 186. The parts are shown in the position which they assume when the solenoid is energized. When the solenoid is deenergized, the member 183 drops until it rests on top of the solenoid. Thus when the solenoid is deenergized there is a gap between the upper end of the operating member 180 and the surfaces 169, 170.

The solenoid 186 is shown as connected to a pair of line wires 187, 188, the connection having a switch or push button 189 interposed therein.

The conductors 126, 127 may also be connected to the line wires 187, 188 through a switch 190. The switch 190 and the push button 189 may be mounted at any place most convenient for the operator of the apparatus.

The apparatus illustrated in Figure 14 may be operated as follows, to carry out the hereinbefore referred to method of making pre-focused lamps. The lamp, with its filaments in predetermined relation to the support 123, is placed with its contacts 134, 135 in engagement with the contacts 124, 125, the skirt portion 140 being interposed between the separated die elements 161, 162, it being assumed that the operating member is out of engagement with the cam surfaces 169, 170. The switch 190 is closed, thereby lighting both of the filaments, if the connections are as hereinbefore described with regard to the lamp 20. The dished shaped member 144 is then brought down on top of the bulb 137 by means of the handle 159 and the lamp is depressed, and permitted to rise, and moved about in horizontal planes, until a desired position is reached. For example, the lamp may be so moved until it is in that position in which an image of the filament 142, thrown upon a screen (not shown), is sharply defined. Under these circumstances the plane defined by the several die means 160 may be so predetermined with respect to the point at which the filament 142 produces a sharp image that that point, and therefore the coincident lighting center of the filament 142, will be in a line normal to the plane of the die means, with that normal line intersecting that plane at a point equidistant from the several die means, and the distance of that point from that plane may be so chosen that it will be the same as the distance of the focal point of the reflector from the plane defined by the points of contact between the surface of the reflector and the lateral extensions on the lamp base, such as the extensions 31, 32, 33 on the lamp 20.

When the lamp 136 has been adjusted to the desired position, the button 189 is pressed thereby energizing the solenoid 186 and causing the operating means 180 to rise and strike the surfaces 169, 170 by reason of the lost motion between the upper end of the member 180 and the surfaces 160, 170, thereby to move the upper ends of the die elements 161, 162 toward each other, against the opposite surfaces of the skirt 140. The die elements thereby strike out from the metal of the skirt 140 lateral extensions 191 similar to the extensions 31, 32, 33 of the lamp 20. When the button 189 is released the operating member 180 descends and the die elements 161, 162 are separated by the spring 173, thereby permitting removal of

the lamp 136, after lifting of the dished member 144. The lamp 136 is now completely finished for use as a pre-focused lamp.

By mounting the die elements 161, 162 on a floating pivot 167, the die elements are permitted to so adjust themselves when operating force is applied thereto that the skirt will not be distorted.

From the foregoing it will be apparent to those skilled in the art that my invention provides a new and improved electric lighting device, made in a new and improved manner by new and improved means, and accordingly accomplishing at least the principal object of my invention. On the other hand, it also will be obvious to those skilled in the art that the particular embodiments herein described may be variously changed and modified, without departing from the spirit of my invention, or sacrificing the advantages thereof.

In general, the disclosure herein is illustrative only, and my invention is not limited thereto. 20

I claim:

1. The method of making a pre-focused electric incandescent lamp having base means provided with means for positioning said lamp with respect to a mounting means, comprising: adjusting to a predetermined position a lamp provided with base means lacking such positioning means, and so changing the form of said base means, while said lamp is in said predetermined position, as to provide a positioning projection extending generally 25 radially outwardly from said base means as originally formed. 30

2. The method of making a pre-focused electric incandescent lamp having base means provided with means for positioning said lamp with respect to a mounting means, comprising: adjusting to a predetermined position a lamp provided with base means lacking such positioning means, and forming a positioning projection on said base means, while said lamp is in said predetermined 40 position, by striking outwardly material of said base means. 35

3. The method of making an electric incandescent lamp having base means provided with means for connecting said lamp to a mounting 45 means, comprising: providing a bulb with base means complete except for connecting means, and then forming generally radially outwardly projecting connecting means on said base means. 50

4. The method of making an electric incandescent lamp having base means provided with means for connecting said lamp to a mounting means, comprising: providing a bulb with base means complete except for connecting means, and then forming connecting means on said base 55 means by striking outwardly, material of said base means. 60

5. Apparatus for making electric incandescent lamps, comprising: means for supporting a lamp having a base initially lacking means for cooperative engagement with a mounting means; and forming means, including a carrier, die means movably mounted on said carrier for movement, in a generally radial direction with respect to the axis of the lamp, and means for mounting said carrier for movement in said direction; said forming means being constructed and arranged to be operable to form means on the base of the lamp for cooperative engagement with a mounting 65 means. 70

6. Apparatus for making electric incandescent lamps, comprising: means for supporting a lamp having a base initially lacking means for cooperative engagement with a mounting means; forming means, including a die, so constructed and 75

arranged that it is operable to form means on the base of the lamp for cooperative engagement with a mounting means; and means, including a lost motion connection, constructed and arranged to operate said die with a hammer blow.

7. Apparatus for making electric incandescent lamps, comprising: means for supporting a lamp having a base initially lacking means for cooperative engagement with a mounting means; and forming means, including a pair of cooperable dies, one of said dies being of the punch type and the other of the matrice type; said forming means being constructed and arranged to be operable to form means on the base of the lamp for cooperative engagement with a mounting means.

8. Apparatus for making electric incandescent lamps, comprising: means for supporting a lamp having a base initially lacking means for cooperative engagement with a mounting means; and forming means, including a carrier, die means movably mounted on said carrier for movement in a generally radial direction with respect to the axis of the lamp, said die means including cooperable punch and matrice dies, and means for mounting said carrier for movement in said direction; said forming means being constructed and arranged to be operable to form means on the base of the lamp for cooperative engagement with a mounting means.

30 9. Apparatus for making electric incandescent lamps, comprising: means for supporting a lamp having a base initially lacking means for cooperative engagement with a mounting means; forming-means so constructed and arranged that it is operable to form means on the base of the lamp for cooperative engagement with a mounting means; and means, including a single actuator, so constructed and arranged that manipulation of said actuator is adapted to hold the lamp on said supporting means and to adjust the lamp, with respect to said forming-means in the general direction of the axis of the lamp and in planes transverse to said axis.

10. Apparatus for making electric incandescent lamps, comprising: means for supporting a lamp having a base initially lacking means for cooperative engagement with a mounting means; forming-means, including a carrier, die means movably mounted on said carrier for movement in a generally radial direction with respect to the axis of the lamp, and means for mounting said carrier for movement in said direction; said forming-means being constructed and arranged to be operable to form means on the base of the lamp for cooperative engagement with a mounting means; and means, including an electroresponsive device, constructed and arranged to operate said forming-means.

11. Apparatus for making electric incandescent lamps, comprising: means for supporting a lamp having a base initially lacking means for cooperative engagement with a mounting means; forming-means, including a die, said forming-means being so constructed and arranged that it is operable to form means on the base of the lamp for cooperative engagement with a mounting means; and means, including an electroresponsive

device, having a lost motion connection with said die, constructed and arranged to operate said die with a hammer blow.

12. Apparatus for making electric incandescent lamps, comprising: means for supporting a lamp having a base initially lacking means for cooperative engagement with a mounting means; forming-means, including a pair of cooperable dies, one of said dies being of the punch type and the other of the matrice type, said forming-means being so constructed and arranged that it is operable to form means on the base of the lamp for cooperative engagement with a mounting means; and means, including an electroresponsive device, constructed and arranged to operate said forming-means.

13. Apparatus for making electric incandescent lamps, comprising: means for supporting a lamp having a base initially lacking means for cooperative engagement with a mounting means; and forming-means, including a carrier, a pair of cooperable dies, both movably mounted on said carrier for movement in a generally radial direction with respect to the axis of the lamp, and means for mounting said carrier for movement in said direction, said forming-means being constructed and arranged to be operable to form means on the base of the lamp for cooperative engagement with a mounting means.

14. Apparatus for making electric incandescent lamps, comprising: means for supporting a lamp having a base initially lacking means for cooperative engagement with a mounting means; and forming-means, including a pair of cooperable dies, both movable with respect to a lamp supported by said supporting means, one of said dies being of the punch type and the other of the matrice type; said forming-means being constructed and arranged to be operable to form means on the base of the lamp for cooperative engagement with a mounting means.

15. The method of making a pre-focused electric incandescent lamp having base means provided with means for positioning said lamp with respect to a mounting means, comprising: adjusting to a predetermined position a lamp provided with base means lacking such positioning means, said base means including a shell portion and a part extending approximately parallel to and spaced from said shell portion, and so changing the form of said base means, while said lamp is in said predetermined position, as to provide a positioning projection extending generally radially outwardly from said part as originally formed.

16. The method of making an electric incandescent lamp having base means provided with means for connecting said lamp to a mounting means, comprising: providing a bulb with base means including a shell portion and a part extending approximately parallel to and spaced from said shell portion, said base means being complete except for connecting means, and then forming generally radially outwardly projecting connecting means on said part.

HARRY A. DOUGLAS.
